UNITED STATES PATENT OFFICE.

ERNEST A. LOWE, OF PLAINFIELD, NEW JERSEY, ASSIGNOR, BY MESNE ASSIGNMENTS, TO AUTOMATIC SPRINKLER COMPANY OF AMERICA, OF NEW YORK, N. Y., A CORPORATION OF DELAWARE.

AUTOMATIC EXTINGUISHING APPARATUS.

Application filed July 16, 1921. Serial No. 485,398.

This invention relates especially to automatic fire extinguishing apparatus preferably comprising effervescent or foam producing fire extinguishing chemicals which 5 blanket and extinguish fires that might be spread by water and ordinary chemical extinguishers; and the apparatus may, for example, be used advantageously in connection with dipping tanks or other oily inflammable material on which the foam floats or spreads out readily in its extinguishing action, and where it is often of vital importance that the extinguishing devices operate promptly in the event of fire to prevent 10 serious loss. For this purpose it is desirable to have the extinguishing apparatus operated or controlled by rate of rise devices such as a vented air thermostat, which may be used alone or in connection with a fusible link or 15 other definite or fixed temperature thermostat or release. A portable form of device is often advantageous, and a pail or container may be arranged to support or contain two normally separated chemicals or 20 liquids which may produce the fire extinguishing foam on mixture, while an upper or release chamber containing or supporting the releasing or controlling devices, may be connected to the bottom chamber or container to form a convenient or portable unit.

In the accompanying drawing showing in a somewhat diagrammatic way the preferred form of this invention, Fig. 1 is a vertical section through one illustrative apparatus. 25 Fig. 2 is a detail transverse section thereof, taken along the line 2—2 of Fig. 1.

Referring first to Fig. 1, the bottom element or pail 1 may be formed with a series of discharge holes 38 adjacent its upper portion and a supporting ring or device 36 may be arranged or secured to the pail bottom, and provided with holes or other channels 37, so as to conveniently support a breakable container 32 of glass or other suitable material, and preferably having a thin breaking socket such as 35 adjacent the bottom. This container which may extend above the bottom pail or element in some cases may advantageously contain the acid reacting 40 element or chemical 34, such as suitable acid or aluminum sulphate solution where foam producing chemicals are employed. The cooperating chemical 54 may be arranged in

the pail bottom and may be any suitable carbonate solution such as sodium bicarbonate with which may be incorporated licorice root juice or other emulsifying agent for foaming purposes, although of course other suitable fire extinguishing chemicals may be employed which for some purposes preferably produce foam or bubbles of a more or less permanent character containing non-inflammable gases. For some purposes it is desirable to prevent evaporation of or moisture absorption by these chemicals and for 55 this purpose thin films or layers of heavy oil 60 33 and 53 may be used on top of the chemicals.

The upper element or release chamber 4 of suitable sheet metal for instance may have 65 a connected junction portion 3 fitting within the top of the pail and connected to a bottom partition, which may advantageously comprise a covered flange 2 of such size and shape as to accommodate the top of the acid jar 32. The releasing or controlling devices are arranged within and secured to the release chamber, so as to be protected thereby, and it is convenient to have the bottom partition removably connected to this release chamber as by the bolts 39, so as to gain access to these parts when desired. The control devices are preferably arranged 70 adjacent the upper part of the release chamber, and may advantageously be secured on top of the same in some cases, where they are exposed to the heat and atmospheric conditions near the ceiling or other partition above the dipping tank or other device to be protected. For this extreme service 75 where volatile inflammable oils or solvents are used by dipping tank methods, it is vitally important to extinguish any fire before the body of the inflammable liquid is substantially heated, so as to vaporize substantial amounts of the material; and thus prompt operation of the extinguishing apparatus is of special importance, especially 80 where foam extinguishing material is used which can be advantageously discharged 85 upon and readily spread over burning oily or light inflammable liquid. Any suitable form of rate of rise thermostat is desirable 90 for this service; since even in a cold room the burning oil or solvent at once produces 95 a temperature rise of many degrees per 100

minute, so that the extinguisher often operates in a few seconds, much before a serviceable fusible link or fixed temperature release could function. A vented air thermostat release is preferably used, the air chamber 11 of such a device being shown as mounted above the release chamber 4 and within a cage or skeleton protecting case 10 secured to the top of the release chamber. 5 The air tube 12 may extend down into the release chamber and be connected as by the coupling 13 with a vented diaphragm chamber 15 having therein or adjacent thereto any suitable vent shown diagrammatically as 74, 15 and containing the light metal diaphragm 16 so that this vented air system raises the diaphragm on increases of temperature at a rate exceeding the safe or normal rate allowed for, and this raises the pin 17 so as to 20 swing the release lever 18 about its pin 19. The other end of this release lever then moves down below the end 21 of the latch lever 20, so that this lever can swing horizontally about its supporting pin 22 under 25 the action of a suitable spring if desired, so as to carry its end 23 out of the path of its catch 24 on the swinging weight 25 shown in Figs. 1 and 2. This weight is then released and swings down in the direction of the arrow, so that when it assumes its dotted line 30 position shown in Fig. 2, it strikes the end of the impact lever 30 and turns this about its pivot 29, so as to give a quick and strong impulse to the impact rod 31. The lower end of this rod, which extends through the flange top for guidance, punches out or breaks the socket 35 in the bottom of the acid container 32 and effects the mixture of the extinguishing chemicals which foam out through the 35 discharge holes 38, so that the light and buoyant fire extinguishing foam is delivered into the dipping tank below.

In some cases a fusible link or fixed temperature thermostat may also be used, the 45 fusible link elements 42, 44 being shown as connected by solder or the like 43, so that this link which may be secured on the projection 40 is released at an excessive temperature independently of the rate of rise 50 of temperature and allows the releasing arm 46, extending through the hole 45 in the lower link element, to drop as the arm swings about its pin 47 under the action of the spring 49. The connected catch 48 then moves away from the auxiliary weight 52 so 55 that this weight can descend its pin 51, under the action of the spring 50 if desired, so as to strike and operate the impact lever 30 as before described. As indicated in Fig. 2 a 60 squared key end 28 may be arranged on the weight 25 so as to be engaged by a key inserted through a hole in the release chamber to restore the weight in its set position shown in full lines after it strikes the stop 55 on 65 the bracket 26 for example. Similar brackets

56, 57 may support the diaphragm chamber or other parts of the apparatus from the release chamber top for example.

This invention has been described in a preferred form, to the details of which disclosure the invention is not of course to be limited, since what is claimed as new and what is desired to be secured by Letters Patent is set forth in the appended claims.

I claim:

1. In automatic fire extinguishing apparatus adapted to be used adjacent dipping tanks or generally similar highly inflammable material, a portable container comprising a bottom pail having adjacent its upper portions a series of discharge holes and having a supporting ring on its lower inside portion to support a breakable open top container for one of the normally separated foam producing chemicals, and 80 a release chamber adapted to fit the upper part of said pail and having a bottom partition and upwardly projecting covered flange therein to accommodate the upper portion of said breakable container, an air chamber and a fusible link mounted on top of said releasing chamber to be exposed to the adjacent heat and air conditions, an impact rod engaging the bottom of said breakable container and extending through 85 and guided by the top of said flange, an impact lever cooperating with said impact rod, weights cooperating therewith, a vented diaphragm chamber connected to said air chamber and mounted within said releasing chamber and releasing devices controlling said weights and operated by said diaphragm and said fusible link to promptly discharge such fire extinguishing material 90 on abnormal rate of temperature rise. 105

2. In automatic fire extinguishing apparatus adapted to be used adjacent dipping tanks or generally similar highly inflammable material, a portable container comprising a bottom pail having adjacent its upper portions a series of discharge holes and having a breakable container for one of the normally separated foam producing chemicals, and a release chamber adapted to fit the upper part of said pail and having a bottom partition and upwardly projecting covered flange therein to accommodate the upper portion of said breakable container, an air chamber mounted on top of said releasing chamber to be exposed to the adjacent heat and air conditions, an impact rod engaging said breakable container and extending through and guided by the top of said flange, an impact lever cooperating with said impact rod, weights cooperating therewith, a vented diaphragm chamber connected to said air chamber and mounted within said releasing chamber and releasing devices controlling said weights and operated by said diaphragm to promptly discharge such 110 115 120 125 130

fire extinguishing material on abnormal rate of temperature rise.

3. In automatic fire extinguishing apparatus adapted to be used adjacent dipping tanks or generally similar highly inflammable material, a container comprising a bottom member having adjacent its upper portions a series of discharge holes and containing normally separated chemicals and 10 a release chamber adapted to fit said bottom element, an air chamber mounted on said releasing chamber to be exposed to the adjacent heat and air conditions, a vented diaphragm chamber connected to said air chamber and mounted within said releasing chamber and cooperating releasing devices to effect the mixture of said chemicals.

4. An automatic fire extinguishing apparatus comprising separated containers for 20 chemicals adapted when brought into communication to produce an effervescent fire extinguishing medium, means to provide for the escape and dispersion of said effervescent medium, and mechanism for effecting 25 a means of communication for said chemi-

cals from one of said containers to the other, said communication effecting mechanism including a rate of rise thermostat and a fixed temperature thermostat, each of said thermostats being capable of controlling said 30 communication effecting mechanism independently of the other.

5. A portable automatic fire extinguishing apparatus having all of its component elements combined in a compact self-contained 35 unit comprising separated containers for chemicals adapted when brought into communication to produce an effervescent fire extinguishing medium, means to provide for the escape and dispersion of said effervescent 40 medium, and mechanism for effecting a means of communication for said chemicals from one of said containers to the other, said communication effecting mechanism including a rate of rise thermostat and a fixed 45 temperature thermostat, each of said thermostats being capable of controlling said communication effecting mechanism independently of the other.

ERNEST A. LOWE.
